UNITED STATES PATENT OFFICE.

HAROLD D. DAVIS AND CHARLIE L. FOWLER, OF ATHENS, TENNESSEE.

LATHE CENTER.

Application filed May 23, 1927. Serial No. 193,594.

The present invention relates to improvements in lathe centers, and the primary object of the invention resides in the provision of an improved type of dead center for lathes wherein the center proper is revolvably mounted in anti-friction bearing means for free rotation with the work being supported by the center.

A further object of the invention is to provide a lathe center as set forth embodying a construction whereby no adjustment due to wear is required, and embodying features whereby lubrication of the parts may be readily accomplished without the need of special oiling means.

A further object of the invention resides in the provision of an improved lathe center wherein a single roller bearing serves to carry both radial and thrust loads of a revolvable center proper.

A still further object of the invention is to provide an improved lathe center as defined which may be very economically manufactured owing to the simplicity of the device, and one wherein lubrication is permitted merely by relative longitudinal movement of the center proper with its carrying member.

Other objects and advantages of the invention will be apparent during the course of the following detailed description, taken in connection with the accompanying drawings forming a part of this specification and in which drawings:

Figure 1 is a side elevation of the preferred form of lathe center and showing the center proper withdrawn for its fullest extent of longitudinal movement from its carrier portion for permitting of lubrication of the roller bearing mounting for the center proper.

Figure 2 is a central longitudinal section through the lathe center as illustrated in Figure 1 and showing the parts in position during use of the center.

Figure 3 is a central longitudinal section through a slightly modified form of the invention and showing a two part construction for the shank or stem portion of the center proper.

Figure 4 is a transverse section taken substantially on the line 4-4 of Figure 2 and illustrating more particularly the construction of the outer end of the sleeve or carrier portion for the center proper.

Figure 5 is a central longitudinal section through a further modified form of the in-

vention and showing a slightly modified type of retaining means for the center proper.

Figure 6 is a central longitudinal section showing a still further modified form of retaining means for the center proper.

Figure 7 is a central longitudinal section through a still further form of lathe center and showing a slightly modified form of roller bearing mounting for the center proper.

Figure 8 is a transverse section on line 8-8 of Figure 6 and looking in the direction of the arrows.

Referring to the drawings in detail, and wherein similar reference characters designate corresponding parts throughout the several views, the improved lathe center is shown as embodying a main body or carrier portion A, a center proper B, a bearing C for revolvable mounting of the center proper within the carrier portion A, and a retaining means D for retaining the portions A and B in assembled relation and permitting limited relative longitudinal movement thereof.

Referring first to the preferred form of the invention as illustrated in Figures 1 and 2, and more specifically to the main body or carrier portion A, the same embodies a sleeve 10 having a rearwardly tapering external surface for fitting in the usual tail stock of the lathe. The outer end of the sleeve 10 is enlarged as at 11 and provided at its outer face with an annular pocket 12 having a reduced inner end for forming an internal annular shoulder 13 spaced slightly from the inner end of the pocket. Extending axially through the sleeve 10 and concentric with the annular pocket 12, is a circular bore 14 which extends from the pocket 12 to the inner flat end face 15 of the sleeve.

Referring now to the center proper B, the same embodies a conical shaped tip or head 16 and a spindle 17 which projects from the inner face of the head 16 in axial alignment with the center point 18. The spindle 17 is formed at its forward end with a bearing portion 19 being of a length substantially equal to the depth of the pocket 12, and extending inwardly from the bearing portion 19 is a reduced stem or shank portion 20 of equal diameter throughout its length and which stem is of a length greater than the length of the bore 14 through which the stem extends. As will be observed, the stem portion 20 is rotatably mounted within the bore of the sleeve.

10 and projects for a substantial distance rearwardly past the end face 15 when the center proper B is in assembled relation with its carrier portion A. Provided at the inner 5 face of the head 16 and concentric with the axis of the bearing portion 19, is an annular groove 21 having its smaller diameter greater than that of the bearing portion 19 for forming an annular abutment 22 encircling the 10 outer end of the bearing portion 19. It is preferred that the conical tip or head 16 at its inner end be of a diameter substantially equal to that of the enlarged sleeve portion 11 in order that the outer peripheral portion of 15 the rear face of the tip will be disposed in confronting relation with the outer edge of the enlargement 11. As will be observed in Figure 2 the annular groove 21, when the portions A and B are in assembled relation, is 20 disposed in confronting relation with the annular pocket 12 of the carrier portion A. While such would appear obvious upon observing the drawings, it may here be well to state that the spindle 17 is formed as an integrally 25 part of the head 16.

Referring now to the bearing C for revoluble mounting of the center proper B within the carrier portion A, the same is of the usual roller bearing type and embodies 30 companion inner and outer tapered braces 25 and 26 respectively forming tracks for the cylindrical roller elements 27. The bearing C also embodies the usual retainer or spacer 28 for keeping the roller elements 27 evenly 35 spaced and in line with the tracks formed by the races 25 and 26. This bearing C by reason of the tapered tracks of the races 25 and 26 serves as a combined thrust and radial bearing for the load carried by the center proper 40 B, and as will be observed in Figure 2, the races 25 and 26 are arranged so that the axes of the rollers 27 extend in diverging relation toward the center point 18. The inner race 25 is of a width slightly less than the length of 45 the spindle bearing portion 19 and is mounted on the bearing portion 19 by means of a wedging fit and abuts at its outer end the annular abutment 22. This pressed fitting of the race 25 upon the bearing portion 19 will cause the 50 race to turn with the center proper B and in which pressure upon the head 16 is transmitted to the race 25 by means of the annular abutment 22. The outer race 26 is pressed into the annular pocket 12 with its inner edge 55 abutting with the annular shoulder 13, and which annular shoulder 13 serves to prevent inward movement of the race 26 due to the inward pressure exerted on the race by means of the roller elements 27. The retainer or 60 spacing ring 28 and which serves for retaining the rollers 27 assembled upon the inner race 25 when the carrier A is removed from the center proper B, projects at its outer edge for a short distance into the annular groove 65 21 and for a purpose to be subsequently ex-

plained. The annular groove 21 aside from providing a construction whereby the outer edge of the retaining ring 28 will be prevented from having bearing contact with the rear face of the head 16, also forms a retaining 70 groove for a heavy lubricant such as grease for proper lubrication of the roller bearing C.

By so having the retainer or spacing ring 28 project at its outer edge for a short distance into the annular groove 21, such serves 75 as means for conveying the lubricant in the groove 21 to the rollers 27, and by reason of the ring spanning the space between the rear face of the head 16 and forward edge of the carrier A, such will prevent foreign matter such as cuttings from the lathe tool from readily entering the annular groove 21 and eventually working into the races for the 80 roller bearings.

By observing Figure 2 it will be seen that 85 when the carrier portion A is moved outwardly along the stem 20 until the outer race 26 properly engages the rollers 27, that a small clearance is provided between the rear edge of the head 16 and forward edge of the 90 sleeve enlargement 11. This small clearance space between the portions A and B will practically exclude entrance of any foreign matter into the roller bearing C when the lathe center is in use.

Referring now to the retaining means D for securing the sections A and B in assembled relation, and more particularly to the form of retaining means for the type of lathe center as illustrated in Figures 1 and 2, the same 100 consists of a washer 30 held against longitudinal movement off the inner end of the stem portion 20 by means of a suitable cotter pin or key 31. This cotter pin 31 extends through the stem 20 at a location whereby a suitable clearance such as at 32 in Figure 2 is provided between the washer 30 and the end face 15 of the sleeve 10 when the center proper B is in operative relation with the carrier portion A. This spacing of the 105 washer 30 permits of slight relative longitudinal movement of the sections A and B, and when the center proper is withdrawn for its limit of longitudinal movement as illustrated in Figure 1, sufficient clearance is provided between the rear edge of the head 16 and enlargement 11 for the positioning of a lubricating grease within the annular groove 21 for lubrication of the roller bearing C. Thus it will be seen that the means D aside from retaining the sections A and B in assembled relation, is so positioned as to permit of slight relative longitudinal movement of the sections A and B for allowing 110 lubrication of the bearing C.

With reference to the form of lathe center as illustrated in Figure 3, the sleeve 10' has its bore 14' enlarged at its outer end as at 34 for revolubly receiving the stub shank 20' of the center proper B. This stub shank 130

20' and which as will be observed is of approximately one-half the length of the sleeve 10', is provided at its inner end with a threaded bore 35 for receiving the threaded inner 5 end 13 of a stem 37 which extends through the bore 14' with its end extending past the inner end face of the sleeve. Mounted on the projecting portion of the stem 37 and spaced from the inner end face of the sleeve, is a 10 retaining means as illustrated in Figures 1 and 2 and embodying a washer 30' held against movement off the stem by means of a suitable cotter pin 31'. The bore 35 of the stub shank 20' is of a depth so that when the 15 stem 37 is threaded into the bore the washer 30' will be spaced sufficient distance from the inner end of the sleeve 10' as to prevent possible locking of the center proper within the carrier A and also allow for relative longitudinal movement of the sections A and B 20 for a purpose as defined in the construction of the form of lathe center as illustrated in Figures 1 and 2.

With the form of lathe center as illustrated 25 in Figure 5, the retaining means D' is in the form of a cap screw embodying a head 40 and a shank or stem portion 41 having a threaded end for threaded connection within the threaded bore 35 of the stub shank 30 20'. The shank or stem 41 is of such length that the head 40 is spaced from the inner end face 15' of the sleeve 10', and a roller bearing 42 is preferably mounted on the stem 41 between the head 40 and end face 35 15' for allowing free rotation of the member D when moved outwardly of the member A. It will also be observed that relative longitudinal movement of the members A and B is permitted by the spacing provided between 40 the end face 15' and the bearing 42.

With the form as illustrated in Figure 6, the bearing 42 has been omitted and the shank 41 of the cap screw shortened so that when the inner end of the shank 41 is threaded into 45 the bore 35 for its fullest extent, the head 40 will be spaced from the end face 15' for allowing relative longitudinal shifting of the members A and B.

By so having the central portions as illustrated in Figures 3, 5 and 6 of two piece construction, such will permit of more economical manufacture of the lathe centers since less stock is lost in machining the center proper B by reason of forming the shank portion of 55 a length considerably less than the full length of the carrier portion A.

With the form of lathe center as illustrated in Figure 7, the bearing C' is of the double roller bearing type with one portion of the 60 bearing extending into the annular pocket 12 of the member A, and the head 16' having an annular pocket 45 provided in the rear face for receiving a portion of the double roller bearing.

65 From the foregoing description it will be

apparent that a novel and improved type of lathe center has been provided wherein the center proper is revolvably mounted in anti-friction bearing means for free rotation with the work being supported by the center, one 70 wherein lubrication is permitted by reason of relative longitudinal movement of the center proper with its carrier portion and which longitudinal movement eliminates possibility of the center proper and its carrier member to 75 have a tendency to become locked with one another, and one wherein a single protected roller bearing serves to carry both radial and thrust loads of the revolvable center proper.

Various changes in the shape, size and arrangement of parts may be made to the specific forms of the invention herein shown and described, without departing from the spirit of the invention or the scope of the following claims. 85

We claim:

1. A lathe center comprising a tubular carrier portion having a pocket opening at its outer end, a center proper including a head having an annular groove in its inner face in confronting relation to said pocket and a spindle rotatable in the carrier portion, an anti-friction roller bearing arranged in said pocket for revolvable mounting of the center proper in the carrier portion and including 90 a retaining ring having its outer edge projecting slightly into said annular groove, and means for retaining the center proper in position within the carrier portion and permitting free limited movement of the center head 100 away from the outer end of the carrier portion. 100

2. A lathe center comprising a tubular carrier portion having a pocket opening at its outer end, a center proper including a head 105 having an annular groove provided at its inner face in confronting relation to said pocket and a spindle rotatable in the carrier portion, said head having its inner face slightly spaced from the outer end of the carrier portion, an anti-friction roller bearing for revolvable mounting of the center proper in the carrier portion, including an outer race secured in the pocket of the carrier portion, an inner race carried by the center spindle, roller 110 elements between the races, and a retaining ring for the rollers movable with the inner bearing race and having its outer edge projecting for a short distance into the annular groove of the center head, and means for retaining the carrier portion and center proper 115 in assembled relation and allowing limited relative longitudinal movement thereof. 120

3. A lathe center comprising a tubular carrier portion having a pocket opening at its outer end, an outer bearing race fixed in the pocket, a center proper including a head having an annular groove provided in its inner face in confronting relation to said pocket 125 and a spindle rotatable in the carrier portion, 130

- said spindle including a bearing portion adjacent said head, an inner bearing race rigidly carried by the bearing portion, roller elements arranged between the inner and outer bearing races for normally retaining the center head slightly spaced from the outer end of the carrier portion, said roller elements having their axes extending in diverging relation toward the center head point, a retaining ring for 10 the roller elements and projecting slightly into the annular groove of the center head, and retaining means for the carrier portion and center proper for retaining the same in assembled relation and permitting limited 15 free outward movement of the center head for increasing the spacing between the head and outer end of the carrier portion.
4. A lathe center comprising a tubular carrier portion having a pocket opening at its 20 outer end, a center proper including a head having its inner face in confronting relation to said pocket and a stem portion rotatable in the carrier portion and projecting past the inner end face thereof, an anti-friction roller 25 bearing arrangement in said pocket for revolvable mounting of the center proper in the carrier portion with the center head spaced slightly from the outer end of the carrier portion, and a retaining means carried by the 30 rearwardly projecting end of the spindle and spaced from the inner end face of the carrier portion for allowing limited outward movement of the center proper with respect to the carrier portion.
- 35 5. A lathe center comprising a tubular carrier portion having a pocket opening at its outer end, a center proper including a head

having its inner face in confronting relation to said pocket and a stem portion rotatable in the carrier portion and having a threaded bore at its inner end, an anti-friction bearing arranged in said pocket for revolvable mounting of the center proper in the carrier portion against radial and thrust loads, a shank having threaded connection with the bore of 40 said stem and projecting past the inner end face of the carrier portion, and an abutment carried by the shank in spaced relation from the inner end of the carrier portion for allowing limited outward movement of the center proper with respect to the carrier portion. 45

6. A lathe center comprising a tubular carrier portion having a pocket opening at its outer end, a center proper including a head having its inner face in confronting relation to said pocket and a shank portion extending into the carrier portion and having a threaded socket at its inner end, an anti-friction roller bearing arranged in said pocket for revolvable mounting of the center proper in the carrier portion with the center head spaced relatively close to the outer end of the carrier portion, and means for retaining the center proper in assembled position with the carrier portion and permitting for slight movement 55 of the center head away from the outer end of the carrier portion, comprising a cap screw including a head normally spaced from the inner end of the carrier portion and a stem having threaded connection at its inner end 60 in the bore of said shank. 65
